LOOSE-LEAF BINDER MECHANISM

Hermann Frodermann, Hedrichsdorf 6, Espelkamp-Mittwald, Westphalia, Germany
Filed June 19, 1962, Ser. No. 203,596
Claims priority, application Germany, June 19, 1961,
F 34,202
2 Claims. (Cl. 129—24)

The present invention relates to a loose-leaf binder mechanism.

Loose-leaf binder mechanisms are known in which the mechanism is fastened by means of rivets to the back of a book cover or in which the back of the book cover is formed with a guide rail into which the loose-leaf binder mechanism is pushed to fasten the mechanism to the book cover. Both ways of connecting the loose-leaf binder mechanism to a book cover are complicated and expensive and especially the attachment of the mechanism by rivets to the cover gives an unsightly appearance of the arrangement.

The present invention aims to overcome this disadvantage of loose-leaf binder mechanism known in the art and to provide for such a mechanism which can be easily fastened to a book cover without forming holes in either the cover or the mechanism for inserting fastening rivets therethrough.

It is an object of the present invention to provide for a book binder mechanism which can be conveniently fastened to a book cover.

It is a further object of the present invention to provide for a loose-leaf binder mechanism which consists only of a few rugged parts which can be manufactured and assembled at reasonable cost and which will stand up under extended use.

It is an additional object of the present invention to provide for such a loose-leaf binder mechanism including ring halves which can be closed and opened for inserting perforated sheets in the mechanism and in which the ring halves are properly held in the closed position thereof.

It is yet an additional object of the present invention to provide for a loose-leaf binder mechanism as mentioned above in which no separate spring members are necessary for holding the ring halves in the closed position.

With these objects in view, the loose-leaf binder mechanism according to the present invention comprises essentially elongated support means, a pair of elongated rails superimposed on the elongated support means and having each an inner edge face abutting against the inner edge face of the other of said pair of rails, a pair of ring halves fastened spaced from each other to each of said rails projecting upwardly therefrom and having a free end adapted to abut against the free end of the corresponding ring half on the other of the rails, and cooperating means on opposite ends of the elongated support means and on opposite ends of each of the rails for mounting the rails on the support means movable between a closed position in which the free ends of the ring halves respectively fastened to the rails are held in abutting relationship and an open position in which the free ends are spaced from each other.

Preferably, the elongated support means of the loose-leaf binder has a flat bottom face which is adapted to be sealed to the back of a book cover and such sealing may be conveniently carried out, when the support means in the book cover is made from plastic, by a heat sealing operation. In this case it is preferred to form a flange projecting laterally from the bottom of the sup-

2

port means to thus facilitate heat sealing of the support means to a book cover.

The cooperating means on the support means and the rails preferably include a pair of grooves formed in each of a pair of projecting members at opposite ends of each support means and cooperating with a pair of trunnions respectively projecting from opposite ends of each of the rails. The pair of grooves in each of the projecting members are downwardly inclined toward each other and the trunnions on each rail are aligned along a common axis preferably located closely to the outer edge of each rail.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings in which:

FIG. 1 is a perspective partial view of the loose-leaf binder according to the present invention;

FIG. 2 is a side view of the loose-leaf binder shown in FIG. 1;

FIG. 3 is a top view of the loose-leaf binder shown in FIG. 1;

FIG. 4 is a section taken along the line IV—IV of FIG. 3 and showing the mechanism in closed position;

FIG. 5 is a sectional view taken along the line V—V of FIG. 3 and showing the mechanism in open position;

FIG. 6 is a partial top view of a modified construction of the rails shown in FIGS. 1-3 and in which the rails are shown in unassembled position separated from each other;

FIG. 7 is a cross section of FIG. 6 taken along lines VII—VII; and

FIG. 8 is a cross section similar to FIG. 7 but showing a slightly modified construction.

Referring now to the drawings and especially to FIGS. 1-5 of the same, it will be seen that the loose-leaf binder mechanism of the present invention basically comprises elongated support means including an elongated base member 1 and a pair of projecting members 4 respectively connected to opposite ends of the base member 1 and projecting upwardly therefrom. The mechanism includes further a pair of elongated rails 2 extending substantially parallel to each other superimposed upon the base member 1 between the projecting members 4. Each of the rails 2 have inner edge faces which abut against each other as can be seen from FIGS. 4 and 5. A pair of ring halves 3 are respectively fastened to the rails 2 in any convenient manner and these ring halves 3 project spaced from each other upwardly from the rails 2 and having each a free end adapted to abut against the free end of the corresponding ring half on the other rail. The mechanism includes further cooperating means on opposite ends of the elongated support means 1, 4 and on opposite ends of each of the rails 2 for mounting the rails 2 on the support means 1, 4 movable between a closed position as shown for instance in FIG. 4 in which the free ends of the ring halves 3 are held in abutting relationship and an open position in which the free ends of the ring halves are spaced from each other as shown in FIG. 5.

The aforementioned cooperating means may include guide grooves 5 formed in the faces of the projecting members 4 which are directed toward each other, and the pair of guide grooves 5 in each of the projecting members 4 extend, as can be best seen from FIG. 4, downwardly inclined toward each other. The cooperating means may include further a pair of trunnions 6 pro-

jecting from opposite ends of each of the rails 2 and being respectively located in the grooves 5 formed in the projecting members 4. The trunnions 6 of each rail are aligned along a common axis extending substantially parallel to the outer edge of each rail 2 and closely adjacent thereto. The inner edge face of each of the rails 2 has an upper face portion and a lower face portion extending outwardly inclined with respect to the upper face portion, as can be best seen in FIG. 4. In the closed position of rails 2 and ring halves 3 as shown in FIG. 4 the rails 2 abut against each other along the upper portion of the inner edge faces thereof, whereas in the open position of rails and ring halves, as shown in FIG. 5, the rails 2 abut against each other along the lower inner edge face portions thereof.

The upper portions of the grooves 5 in each of the projecting members 4 are spaced from each other a distance not greater than the lateral distance between the trunnions 6 projecting from adjacent ends of the two rails 2, so that the upper portions of the inner edge faces of the rails are securely pressed against each other when the rails 2 and ring halves 3 carried thereby are in the closed positions shown in FIG. 4. Preferably, the intersecting lines between the upper and lower inner edge face portions of the rails 2 are located, when the rails 2 and ring halves 3 are in the closed position as shown in FIG. 4, at an elevation slightly lower than that of the axes of the trunnions 6.

When the ring halves 3 are moved from the closed position shown in FIG. 4 to the open position as shown in FIG. 5 by moving the upper ends of the ring halves away from each other, the rails 2 will first pivot about the axes of the trunnion 6 until the aforementioned intersection lines will move to a level higher than the axes of the trunnions and after this movement the two rails will move with a snap action to the position shown in FIG. 5 whereby the trunnions 6 will slide downwardly in the grooves 5. The grooves 5 are preferably slightly curved and inclined towards each other in such a manner that the downward movement of the pinion 6 from the position shown in FIG. 4 to the position shown in FIG. 5 will occur freely and without stressing the trunnions 6 or the rails 2. The upper face of the elongated support member 1 is shaped, as best illustrated in FIG. 5, to provide clearance for the inclined rails 2 in the open position thereof as illustrated in FIG. 5.

The elongated support member 1 has preferably a flat bottom face so that the member 1 can be sealed to the back of a book cover by cementing or heat sealing to the back of a book cover. If heat sealing is intended, the base member 1 is preferably made of plastic material and preferably a flange 1' extending laterally beyond at least part of the bottom of the base member is provided to facilitate heat sealing of a base member to the back of a book cover.

Preferably the rails 2 are made from elastically flexible material, for instance plastic and in this case the projecting members 4 may be integrally made with elongated base member 1 of the support means and the rails 2 may be assembled with the elongated support means 1, 4 by placing a cylindrical member 7 on the top face of the elongated base member 1, by inserting one of the trunnions 6 of the respective rail 2 into the corresponding groove 5 and by then resiliently flexing the rail 2 about the cylindrical member 7 as shown in dash-dot lines in FIG. 2, whereby, after the cylindrical member 7 is removed from the base member 1, the other trunnion 6 of the rail 2 will snap into the opposite groove 5.

If the rails 2 are formed from material which does not lend itself to a flexing as shown in dash-dot lines in FIG. 2, then fastening means have to be provided for fastening one of the projecting members 4 to the base member 1 after the opposite trunnions 6 on each rail 2 have been placed in the corresponding grooves 5 in the projecting members 4.

If the loose-leaf binder of the present invention is to be made to a considerable length, it is preferred to provide on the inner edge faces of the rails 2 cooperating means for connecting the same to each other while permitting movement of the rails from the closed to the open position as mentioned above. Such modifications including cooperating means are shown in the FIGS. 6-8.

FIGS. 6-8 only illustrate parts of the rails and the cooperating means for connecting the inner edge faces thereof to each other, and it is understood that the rails illustrated in FIGS. 6-8 carry each ring halves 3 and that the rails are mounted on elongated support means movable between a closed and an open position as described above in connection with FIGS. 1-5. For clarity's sake, the rails 2 shown in FIGS. 6-8 are shown not abutting against each other as described above, but these rails are shown disassembled and spaced from each other.

The cooperating means on the inner edge faces of rails 2 for connecting the same to each other while permitting movement of the rails from the closed to the open position as described above, include hook means 8 fixed to and projecting from the inner edge face of at least one of the rails 2 and engaging in a corresponding cavity 10 formed in the inner edge face of the other of the rails. Preferably a plurality of hook means 8 and cavities 10 are alternately arranged on the inner edge face of each of the rails 2 to cooperate with corresponding hook means and cavities arranged on the inner edge face of the other of the rails. Hook means 8 and cavities 10 on one rail are staggered with respect to the corresponding hook means and cavities on the other rail so that the hook means on one rail may engage into the corresponding cavity of the other rail.

In the modification shown in FIGS. 6 and 7 the hook means 8 include an upwardly projecting nose 8' and a downwardly extending stepped portion 8" respectively adapted to engage behind ribs 10', 10" respectively projecting toward each other from the upper and lower faces of the cavities 10. These upper and lower faces of the cavities 10 extend substantially parallel to each other spaced from each other at a distance substantially equal to the distance between the point of the nose 8' and the bottom face of the stepped portion 8". To facilitate insertion of hook means 8 with the nose 8' the stepped portion 8" thereon behind the ribs 10', 10" of the cavities 10, another cavity 9 of substantially the same cross-section as the cavity 10 is formed next to each cavity 10 and having a width substantially equal to that of the hook means 8, but this cavity is not provided with ribs 10', 10" so that the rails may be moved towards each other in direction of the arrows A shown in FIG. 6 until the free end face of each hook means 8 abuts against the rear face of the corresponding cavity 9, and by moving afterwards the rails in longitudinal direction with respect to each other until the noses 8' and stepped portions 8" become located behind the ribs 10', 10" of the cavities 10 so that the rails are connected to each other at the inner edge faces thereof.

FIG. 8 shows a cross-section similar to FIG. 7 in which the cooperating means on the inner edge faces of the rails 2 have a slightly modified shape. As can be seen from FIG. 8 the hook means 8 and the cavity 10 are both curved and hook-shaped and the downwardly curved end portion of the member 8 shown at the right rail, as viewed in FIG. 8, is adapted to engage behind the rib projecting upwardly from the bottom face of the cavity shown at the left rail, as viewed in FIG. 8. As described above an additional cavity 9 without any projecting rib is formed next to each cavity 10 to facilitate insertion of the hook-shaped projecting portion 8 and to the corresponding cavity 10 as described above.

In the modifications shown in FIGS. 6-8 the rails are preferably made from plastic material and during tilting of

the rails to the open position thereof the ends of the hook means will be slightly and resiliently deformed.

In the position illustrated in FIGS. 1, 3 and 4 the rails are held by sliding members (not shown) comprising two bars. In the case that the trunnions 6 are in the upper position the bars are led into the grooves 5 and fix the trunnions. The contours of the bars correspond to the lower part of the grooves.

It will be understood that each of the elements described above, or two or more together, may also find a useful application in other types of loose-leaf binder mechanism differing from the types described above.

While the invention has been illustrated and described as embodied in a loose-leaf binder mechanism including a pair of rails abutting against inner edge faces thereof against each other, it is not intended to be limited to the details shown, since various modifications and structural changes may be made without departing in any way from the spirit of the present invention.

I claim:

1. A loose-leaf binder mechanism comprising, in combination, support means including an elongated base member having a pair of top face portions inclined to each other in direction transverse to their elongation and including with each other an angle slightly greater than 180°, and a pair of projecting members respectively connected to opposite ends of said base member projecting upwardly therefrom; a pair of elongated flat rails superimposed on said elongated base member and extending parallel to each other between said projecting members, each of said pair of elongated rails having inner and outer substantially parallel edge faces, said inner edge faces having each an upper face portion adapted to abut against the corresponding upper face portion of the inner edge face of the other rail and a lower face portion outwardly inclined to said upper face portion, and each of said elongated rails having a pair of trunnions respectively projecting from opposite ends thereof aligned along a common axis extending substantially parallel and adjacent to said outer edge face; a pair of ring halves fastened spaced from each other to each of said rails projecting upwardly therefrom and having each a free end adapted to abut against the free end of the corresponding ring half on the other of said rails; and a pair of guide grooves formed in each of said projecting members and being downwardly inclined towards each other and respectively receiving said trunnions so as to mount said rails movable between a closed position in which said rails extend substantially in one plane and in which said trunnions are respectively located at upper portions of said guide grooves which are spaced from each other so as to press in said closed position of said rails the upper portions of said inner edge faces thereof against each other and to hold said free ends of said ring halves in abutting relationship against each other and an open position in which said trunnions are located at a lower portion of said guide grooves and in which said lower face portions abut against each other so that said rails are inclined with respect to each other so that the free end of said ring halves will be spaced from each other, said trunnions being tensionless guided in said grooves, and said grooves, said inner edge faces of said rails and said top face portions of said base member constructed to limit the angular position of said rails.

2. A loose-leaf binder mechanism comprising, in combination, support means including an elongated base mem-

ber having a pair of top face portions inclined to each other in direction transverse to their elongation and including with each other an angle slightly greater than 180°, and a pair of projecting members respectively connected to opposite ends of said base member and extending parallel to each other between said projecting members, each of said pair of elongated rails having inner and outer substantially parallel edge faces, said inner edge faces having each an upper face portion adapted to abut against the corresponding upper face portion of the inner edge face of the other rail and a lower face portion outwardly inclined to said upper face portion, and each of said elongated rails having a pair of trunnions respectively projecting from opposite ends thereof aligned along a common axis extending substantially parallel and adjacent to said outer edge face; a pair of ring halves fastened spaced from each other to each of said rails projecting upwardly therefrom and having each a free end adapted to abut against the free end of the corresponding ring half on the other of said rails; a pair of guide grooves formed in each of said projecting members and being downwardly inclined towards each other and respectively receiving said trunnions so as to mount said rails movable between a closed position in which said rails extend substantially in one plane and in which said trunnions are respectively located at upper portions of the guide grooves which are spaced from each other so as to press in said closed position of said rails the upper face portions of said inner edge faces thereof against each other and to hold said free ends of said ring halves in abutting relationship and an open position in which said rails are angularly inclined with respect to each other and in which said trunnions are located at a lower portion of said guide grooves and in which said lower face portions abut against each other, said trunnions being tensionless guided in said grooves, and said grooves, said inner edge faces of said rails, and said top face portions of said base member constructed to limit the angular position of said rails; and cooperating means on said inner edge faces of said rails for connecting the same to each other while permitting movement of said rails from said closed to said open position and including hook means fixed to and projecting from the inner edge face of at least one of said rails and engaging in corresponding cavities formed in the inner edge face of the other of said rails.
